BALL GAME BOARD OF THE HAND MANIPULATING TYPE

Stanley Sharpless Smith, Jr., P.O. Box 194,
New Canaan, Conn. 06840

Filed June 28, 1973, Ser. No. 374,495

Term of patent 14 years

Int. Cl. D21—01

U.S. Cl. D34—5 SS

FIG. 1

FIG. 2

FIG. 3

FIG. 1 is a perspective view of the ball game board of the hand manipulating type game which embodies my new design:

FIG. 2 is a bottom plan view thereof; and

FIG. 3 is an end view as seen from the right end of FIG. 1.

I claim:

The ornamental design for a ball game board of the hand manipulating type, as shown and described.
